UNITED STATES PATENT OFFICE.

HENRY C. HICKS, OF MINNEAPOLIS, MINNESOTA.

STOCK-CAR.

SPECIFICATION forming part of Letters Patent No. 279,162, dated June 12, 1883.

Application filed October 7, 1882. (No model.)

To all whom it may concern:

Be it known that I, HENRY CLINTON HICKS, a resident of Minneapolis, in the county of Hennepin and State of Minnesota, have invented 5 certain new and useful Improvements in Stock-Cars, of which the following is a specification.

This invention relates to stock-cars; and it consists in the construction and the combination of parts hereinafter particularly described, and then sought to be specifically defined by the claims.

Figure 1 is a cross-sectional view, Fig. 2 is a sectional elevation, and Fig. 3 is a sectional plan view, of the frame of a stock-car with my 15 improvements attached thereto. Fig. 4 is a side view, enlarged, of the feed-rack and water-tank folded up. Fig. 5 is a sectional side view of the same opened out; and Fig. 6 is a plan view of Fig. 5, illustrating the method of construction when a bottom is required thereto.

This invention relates to that class of cars for conveying stock upon railroads, &c., in which a separate stall is provided for each animal and means provided for supplying 25 them with feed and water while in transit.

The invention may be applied to any style of car, either made for the purpose or applied to the ordinary stock-cars at present in use. In the drawings I have shown it applied to an 30 ordinary stock-car box, in which A is the floor, B the upright stanchions supporting the roof-timbers C, and D is the roof.

At intervals corresponding to the width of the space each animal requires in the car, upright metal bars or tubes E' are secured by 35 their lower ends in the floor of the car, on opposite sides, and run up nearly to the roof D, and are bent over at angles at E² and secured by their upper ends, a, to the roof-timbers C or other suitable portion of the car, as shown.

By this means the car is divided up by the bars E' E² into equal spaces, representing stalls for the animals. The bars will be placed with their inner sides even with or outside of the 45 inner line of the stanchions B, so that the bars themselves will offer no obstruction to the interior of the car.

Surrounding each of these bars E' E² is a 50 number of collars, b, each opposite pair of collars upon each opposite pair of the bars being

connected to flexible metal or wooden plates F, and the upper one of each of said sets of plates F supported from the roof of the car by cords or chains c', and the remainder of the plates supported from the upper plate and each 55 other by similar cords or chains, c", so that the collars and plates will assume the position shown in the foreground of Fig. 1 and form partitions between the stalls, as hereinafter shown.

Attached to the outside of each of the collars b are small perforated lugs d, to receive cords e, as hereinafter shown.

Passing through the upper sides of the car, near the roof, and just above the upper ends 65 of each opposite pair of the bars E' E², where they are attached to the timbers C, are shafts G, having square ends g and ratchet-wheels, with which dogs h engage on the outside, so that the shafts may be revolved from the outside and held at any point by the ratchets, and dogs. Secured to these shafts G, just inside the car, are drums H, to which the ends of the cords e, before mentioned, are attached and passed down through the holes in the lugs d 70 on the collars b of each end of each separate stall and attached to the lowermost lugs of each set. By this arrangement the revolving of the shafts G will wind up the cords e on the drums H, raise the lower set of lugs, b, and 75 plate F upon the bars E' E² until the upper edge of the plate strikes the next plate above, and then both will be elevated until the next is reached, and so on until the last plate is 80 reached, when all the plates and collars upon that set or pair of the bars E' E² will be drawn upward upon the inclined upper parts, E², as shown at E², leaving the lower part of the car entirely unobstructed when all the partitions are drawn up to the top of the car, so that all 85 90 the cattle can go out together, which is an advantage, for very often when men attempt to drive out one at a time it will refuse to go, and much difficulty will be experienced and danger run in getting it out; but when they are all free 95 to move out together one will follow the other without being forced or driven.

The angle between that part of the cord e from the drum H to the first set of lugs, d, and the upright part E' of the bars is quite marked, 100

and, unless some device were used to prevent it, the collars *b* would bind upon the bars when the drums *H* were revolved; but to prevent this I arrange grooved pulleys *m* upon the 5 stanchion *B*, next to the bars *E' E²* and just beneath the curved portion connecting the parts *E' E²*, over which the cords are held when the partitions are lowered, and hold the cords nearly parallel with the parts *E'* of the bars 10 when the partitions are drawn up, and prevent cramping at the collars when the partitions are raised. The upper parts of the stanchions *B* will be cut away to permit the ends of the partitions to pass them. By this means each 15 animal can be readily and easily separated from his fellows and provided with a separate stall.

As before stated, the bars *E' E²* will usually be made of gas-pipe or other tubing, whereby 20 lightness and strength are combined. The plates *F* will be of thin metal or wood, so that a certain degree of flexibility will be obtained to prevent their too easy breakage by the pressure of the animals against them.

25 Attached to the ends of the lower plates, *F*, of each stall, upon alternate sides of the car, are combined feed and water racks and tanks, consisting of plates or back *K'*, attached to the lower plates, *F*, and connected by pivoted parallel bars *n* to front plates, *K²*, similar to the backs *K'*. When the partitions are down the lower ends of both plates *K' K²* rest upon the floor of the car, as shown in the left-hand stall in Fig. 2, and then when the partitions are raised upward the back plates, *K'*, will be carried up with the plates *F*, to which they are attached, and the front plates, *K²*, by their weight, will remain upon the floor until the parallel bars *n* draw them toward the plates *K'*, as shown in 35 the right-hand stall of Fig. 2, thereby forming self-folding racks for the feed. Water-tanks *L* are hinged to the upper edges of the front plates, *K²*, and adapted to be turned over inside the racks, as shown in Fig. 4, when not in 40 use.

In Figs. 1, 2, and 3 the second stall from the left-hand side is represented with its combined feed-rack and water-tank folded up and the partition elevated up to the top of the car. The first 50 and fourth stalls have the partitions down in position and the combined feed-rack and water-tank opened out as in use, and the remaining stall, or the third one from the left, with the lower plate, *F*, of its partition raised a short 55 distance, and the water-tank partially turned over inside the front plate, *K²*. Small canvas or other suitable shields, *M*, will be attached between the plates *F*, opposite the feed-racks, to prevent the animals interfering with each 60 other's feed.

The animals will be placed in the cars in the ordinary manner, the head of one being opposite the rear of the next one, and so on throughout the car, thereby necessitating the arrangement of the feed racks and tanks alternately, 65 as shown.

In Figs. 1, 2, and 3 the feed-racks are shown without bottoms, as the hay or cut feed can rest upon the floor of the car; but under some circumstances it may be desired to put bottoms in them, which may be easily done, as shown in Figs. 4, 5, and 6, which represent enlarged views of one of the racks and tanks with a bottom, *K³*, arranged therein.

Foot-boards *N* will be arranged alongside the 75 car, adapted to be held up to support the attendants in caring for or loading or unloading the stock, and folded down out of the way when not in use.

In loading the animals the partitions are all 80 raised up, and when the first animal is in place the first partition is lowered down to shut it into its stall. The next animal is then driven in and the next partition lowered down, and so on throughout the car. Where the doors are 85 in the center, the ends are loaded first, and the last animal driven in at the center; but when the doors are at the end the cars can be loaded entirely from the ends. When the doors are in the center of the car, the center bars, *E' E²*, and 90 attached partitions may be made removable, if desired, so as not to interfere with the use of the car for other purposes than stock-cars. When not used as a stock-car, the partitions will be raised up out of the way, as before stated, 95 so as not to obstruct the interior of the car.

Having described my invention and set forth its merits, what I claim is—

1. In a stock-car, the combination of a series of upright guide-bars angular at their upper 100 ends, partitions adapted to slide upon said bars, means for elevating said partitions, and folding feed-troughs connected to said partitions, whereby they can be elevated with the partitions and supported at the top of the angular 105 bars, substantially as and for the purpose set forth.

2. In a stock-car, the combination of a series of upright guide-bars angular at their upper 110 ends, partitions adapted to slide upon said bars, means for elevating said partitions from the outside of the car, and folding feed-troughs connected to said partitions, whereby they can be elevated with the partitions and supported at the top of the angular bars, substantially as and 115 for the purpose set forth.

3. In a stock-car having a series of stalls formed of upright bars angular at their upper 120 ends, and an elevating partition, the combination therewith of a rope or chain for elevating the partition, and a pulley or roller for the chain to run over, located at the angle of the upright bar, substantially as and for the purpose set forth.

4. In a stock-car having a series of stalls, the 125 combination of straight guide-bars angular at their upper ends, partitions formed of suspended slats, provided at their ends with collars fitting around the guide-bars, and with perforated lugs, a rope or chain passing through said 130 lugs and connected at one end to the lower slot, and a drum and shaft to which the other end

of the rope is connected, for elevating the partition to top of the car, between the top and guide-bars, substantially as and for the purpose set forth.

5. A stock-car having a series of stalls formed of elevating partitions, said partitions being provided with folding feed-troughs, substantially as set forth.

6. A stock-car having a series of stalls formed of elevating partitions, said partitions being provided with folding feed-troughs and water-tanks, substantially as and for the purpose set forth.

7. In a stock-car having a series of partitions, a folding feed-trough connected to the partition and provided with a water-tank hinged thereto, so as to fold with it, substantially as and for the purpose set forth. 15

In testimony whereof I have hereunto set my hand in the presence of two subscribing witnesses. 20

HENRY CLINTON HICKS.
